UNITED STATES PATENT OFFICE.

THOMAS J. FOSTER, OF RIDGEWOOD, NEW JERSEY.

REINFORCED CONCRETE CONSTRUCTION.

Application filed August 28, 1922. Serial No. 584,631.

This invention relates especially to reinforced concrete constructions in which the framework of the building comprises self-supporting skeleton frame members which are sufficiently open to act effectively as steel reinforcement elements for the concrete, and skeleton web beams, columns and the like may be used for this purpose. These elements may be rigidly connected so as to form a self-supporting frame which may not only support the centering or molds for the floor panels, columns etc. but may also support the concrete elevating or distributing devices by which the concrete is carried up and distributed throughout the different floors of the building. Beams and girders of this skeleton web type may advantageously be used for concrete reinforcement in floor construction since such expanded skeleton web beams are valuable reinforcing elements which may be used with or without expanded metal or other reinforcing elements in the floor panels and still such beams have ample strength and rigidity to support the floor centering by wires or other means attached to the beams.

In the accompanying drawing which shows in a somewhat diagrammatic way illustrative embodiments of this invention:

30 Fig. 1 is a perspective view showing several floors of such a concrete building.

Fig. 2 is an enlarged sectional perspective view showing the floor construction.

Fig. 3 is an enlarged horizontal section 35 through one of the concrete columns.

Fig. 4 is a vertical section showing a column cap and girder connection and

Fig. 5 is a top view of the cap taken substantially along the line 5—5 of Fig. 4.

40 The building, which may of course be of any desired size and design, may have a number of reinforced concrete floors 1 supported on the pillars 2 spaced properly to sustain the weight in connection with the girders 4 and floor beams such as 8 which may be spaced apart at suitable intervals throughout each floor. The columns, girders and beams are preferably of the rigid skeleton web type and may be expanded or skeleton web channel or I beams built up or riveted together in the case of girders or columns as shown in Fig. 3 in connection with lattice or other connections such as 24 which may be secured as by the rivets 25 to the flanges of the expanded web I-beam or channels 3. In this way a relatively light rigid reinforcement is formed of sufficient strength to support the connected girders and beams of one or more stories of the building so as to accurately 60 position the different parts of the building frame and also to support the molds or centering therefrom before the concrete is poured. As shown in Fig. 1, such rigid skeleton web columns 3 may have riveted or bolted thereto the girders such as 4, to which the floor beams 8 may be bolted, riveted or otherwise connected (as by the stirrups indicated) so as to form a substantially rigid 65 floor frame work to which the elevator guides 6 may be connected so that the construction elevator 7 may thus be supported in conveying the concrete and other materials to the upper unfinished floors of the building. 70

Fig. 2 shows in greater detail how the floor panels may be cast, the centering being supported in any suitable way from the beams 8 as by the supporting wires 9 which may extend up over the beams so as to hold up the centering supports 10 therefrom. 75 Suitable blocks such as 11 may further support the forms or centering boards 12 for the floor panels. It is in many cases advantageous to form or cast the concrete floor beams out of high strength stone concrete 80 13 which may form the concrete floor beams and penetrate the skeleton webs 28 of the steel reinforcing beams 8, any suitable expanded metal or other reinforcement 17 being used, if desired, above the upper 85 flanges of these beams 8 and throughout the intermediate floor panels. This strong stone concrete may also advantageously extend out six to twelve inches or more to form the floor sections 14 adjacent the concrete beams and a more or less inclined or sloping surface 15 of this concrete may be formed when it is cast or poured so as to facilitate the union of the lighter cinder concrete 16 which may be advantageously used for the intermediate 90 part of the floor panels, these concrete elements being of course thoroughly united as by puddling while the concrete is still wet. The columns may be poured at the same time 95 or before the floor panels which they support and Fig. 3 shows one desirable arrangement in which the steel column reinforcement is embedded in concrete 26 which may be poured or formed around a central form such as the sheet metal pipe 23 wired or 100 105 110

otherwise supported in about the center of the column so that a hollow concrete column is formed having still greater strength in proportion to its weight than a corresponding solid column. Of course after the concrete has set and hardened sufficiently the forms and centering may be removed and used on the corresponding parts of an upper story of the building.

- 10 As shown in Figs. 4 and 5, rigid skeleton web columns of this character may in many cases be formed with additional stiffening cap constructions so as to distribute the load throughout the different elements of this column reenforcement. As shown, the body of the column may comprise two channel or I beam elements 3 having skeleton webs such as the expanded metal skeleton webs 23 shown in Fig. 4 and a heavy steel plate 18 or cap plate 18 may be riveted on top of the column and secured to the channels and plates 19, 20, 27 so as to make this cap plate rigid with all of the metallic column elements and properly transmit thereto the weight of beams or girders such as 4 which may be secured to the cap plate as by the rivets 22 passing through the rivet holes 21 in the cap plate. In some cases it is advantageous to have such cap plates formed with one or more holes through which the concrete may penetrate, such as the hole 29 which facilitates the carrying up of the concrete body of the column and more effectively uniting it to the adjacent concrete beam, floor and wall elements of the building.

This invention has been described in connection with a number of illustrative embodiments, forms, proportions, sizes, parts, materials and methods of connection and use 40 to the details of which disclosure the invention is not of course to be limited since what is claimed as new and what is desired to be secured by Letters Patent is set forth in the appended claims.

45 In the claims the word "concrete" is used to designate any cementitious material of sufficient strength to accomplish the objects desired.

I claim:

1. The concrete floor construction of the beam and panel type comprising skeleton web reenforcing beams adapted to support the molds for the concrete beams and strong concrete cast around said beams and re-enforced thereby to form reenforced concrete beams and having portions cast integral therewith forming the adjacent portions of the floor panels projecting laterally from said concrete beams and lighter concrete forming the intermediate portions of the floor panels and intimately united to such strong concrete.

2. The concrete floor construction of the beam and panel type comprising skeleton web reenforcing beams and strong concrete cast around said beams and reenforced thereby to form reenforced concrete beams and having portions cast integral therewith forming the adjacent portions of the floor panels projecting laterally from said concrete beams and lighter concrete forming the intermediate portions of the floor panels and united to such strong concrete.

3. The concrete floor construction of the beam and panel type comprising rigid skeleton web reenforcing beams adapted to support the centering for the concrete beams and intermediate floor panels and strong stone concrete cast around said reenforcing beams and reenforced thereby to form re-enforced concrete beams and having portions cast integral therewith forming the adjacent portions of the floor panels and light cinder concrete forming the intermediate portions of the floor panels and intimately united to such stone concrete.

4. The concrete floor construction of the beam and panel type comprising rigid skeleton web reenforcing beams adapted to support the centering for the concrete beams and stone concrete cast around said reenforcing beams and reenforced thereby to form reenforced concrete beams and light cinder concrete having portions cast integral therewith forming the intermediate portions of the floor panels and intimately united to such stone concrete.

THOMAS J. FOSTER.
